UNITED STATES PATENT OFFICE.

JOSEPH MATECHIK, OF WEATHERLY, PENNSYLVANIA.

PISTON-RING EXPANDER.

Application filed July 2, 1926. Serial No. 120,151.

This invention relates to devices for expanding piston rings or the like for removing them from the grooves of a piston, etc.

An object is to provide a device of this character which may as readily be applied in position on a piston which has been removed or partially removed from its respective cylinder, and caused to engage the interfitting ends of a piston ring that may have become carboned, corroded or otherwise fouled to an extent that the same is difficult to remove, said engagement, when the device is caused to expand, serving to forcibly separate the ends of said ring and pull the same outwardly from the groove in a manner to eventually free the entire ring and permit same to be readily removed.

Another object is to provide for interchanging the expanding means so that the device is applicable for use on rings of different diameters and widths and having different kinds of joints or interfitting ends.

A full and complete understanding of the invention may be obtained from a consideration of the following detailed description, taken in connection with the accompanying drawing forming a part of this specification, it being understood that while the drawing shows a practical form of the invention, the latter is not to be confined to strict conformity with the showing thereof, but may be changed or modified, so long as such changes or modifications mark no material departure from the salient features of the invention, as specifically pointed out in the appended claims.

In the drawings, in which similar reference characters designate corresponding parts throughout the several figures:—

40 Figure 1 is a plan view of the device partly in section showing the device in use for expanding a piston ring to remove same from the groove of a piston.

Figure 2 is a transverse sectional view of 45 the device, as shown in Figure 1, the piston ring being indicated in dotted lines.

Figure 3 is a perspective view, a portion of the split ring being omitted.

50 Figure 4 is a detail perspective of one of the interchangeable expanding members used in connection with the device.

Referring to the drawing there is shown a 55 split ring 1 formed of suitable metal having sufficient strength and resiliency and of a diameter to accord with the size of the piston rings to be handled, the outer face of said

ring being preferably rounded to avoid injury to the hands of the operator.

The inherent tendency of the ring is to normally hold each end 2 in abutting relation to each other, and flush with each of said ends is an outstanding, detachable lug 3, the inner faces of said lugs being normally arranged perpendicular and adapted likewise to abut against each other.

Each of the lugs 3 is preferably rectangular in cross section, and each is provided with an integrally formed, arcuate base portion 4 which is curved to conform to the curvature of the split clamping ring 1, and is provided with a channel or seat 5 so that one side face of the ring is flush with one side face of each of the base members 4, thus offsetting the major portion of the lugs and base members to one side of the said ring, and such offsetting is of particular importance in the use of the invention in applying the same for the purpose of expanding a piston ring in a manner to be fully set forth.

The inner, arcuate faces of the lugs 3 are each provided with a radially disposed socket 6 adjacent to one edge thereof and in line with the ring 1, while the outer end of the extensions or base portions 4 are each provided with an aperture 7 in line with the socket 6 and, in order to permit of the easy and quick attachment of different pairs of lugs to the spring ring 1, the latter is provided adjacent to the ends thereof with outstanding pins or studs 8 which are adapted to snugly fit in the sockets 6 and with apertures 1^a which align with the aforesaid apertures 7 of the lugs. The apertures 1^a are countersunk on the inner side of the ring for the reception of the bevelled head of a screw or bolt 9, which is adapted to receive a wing nut on its outer end for binding the lugs in place.

The offset portions of the base members 4 are provided along their edges with inwardly extending flanges 11 which thus defines a space or seat between the same and the inner side of the ring 1 for the reception of detachable plates 12 of different kinds depending on the kind of piston ring to be removed from a piston.

Each plate is curved to fit the seat and is provided between its ends with an outwardly extending screw 12^a which is terminally fixed to the plate and is adapted to extend through an aperture 12^b formed in the base of each lug, said screw or bolt being threaded at its outer end where extending through the base

member for the reception of a wing nut 12^c for binding the plate in the seat and permitting of their ready removal and replacement.

The plates 12 are provided at their outer 5 ends with inwardly extending stop lugs or abutments 13, the same being located adjacent to that edge which fits against the aforesaid flange 11, while at their inner ends the plates are provided with inwardly directed fingers 10 14 which have their free ends turned back to provide hooks or lips 15.

When the device is being used for the removal of piston rings and the proper plates have been attached in their seats, the stop lugs 15 or abutments 13 are adapted to bear against the side of the piston ring 16 and hold same up against the side of the ring 1, as shown in Figure 4 of the drawing, and the fingers 14 are introduced in between the ends of said ring with 20 the lips 15 engaging below the overlapped ends 15^a of the ring and when the lugs are separated, in a manner to be explained, it will be seen that the said overlapped ends of the piston ring 16 may be forced out of their 25 respective grooves 17 as usually formed in the piston 18, as clearly shown in Figure 1 of the drawing.

To render the device generally useful on piston rings of different diameters and widths 30 and those having different kinds of inter-fitting end portions, it will be seen that a larger or smaller diameter ring 1 may be substituted by merely removing the thumb nuts 10 and also that the plates 12 may be readily substituted 35 for a pair having the abutments of greater or less width to engage with the side of the piston ring and hold the same steady while being expanded for removal or to expand new and perfect piston rings to enable 40 the same to be passed over the end of a piston, in an obvious manner, and it will be further seen that the width and location of the fingers 14 may be different on the different plates so as to readily enter between the slightly 45 separated ends of the piston ring, the finger on one plate being staggered with relation to the finger of the coating plate.

In order to force the lugs 3 away from each other, as in expanding a ring 16 to remove 50 the same from a piston, a thumb bolt 19 is employed, said bolt having substantially one-half of its length threaded, as at 20, and adapted to traverse a threaded opening 21 formed in one of the lugs. A smooth opening 22 is formed in the other lug 3, said elongated opening or slot being closed at each 55 end and extending longitudinally of the lug or perpendicularly to the ring and cylinder.

The threaded end of the bolt is adapted to 60 engage an abutment on the lug having the opening 22, so that when the bolt is turned by means of wings 24, the lugs will be forced apart and the ring expanded.

The lug having the elongated opening 22 is 65 further provided with a transverse, open slot

27 formed therein and extending from side to side, the inner end of the same extending beyond the inner end of said opening 22 and when the device is to be used for expanding a piston ring that may have become carboned 70 or otherwise held in the groove and is difficult to remove, a small metal plate 28 is placed in said slot 27, to close the opening 22 and the bolt 19 is reversed and first threaded through the threaded opening 21, when the end of the 75 bolt will bear against said plate 28 and, when further turned, will cause a separation of the lugs with a consequent forcible opening of the piston ring, after the lips 15 have been 80 properly engaged therewith, as clearly shown in Figure 3. The plate 28 is provided with a flange 29 to remove same from the slot 27.

In some instances where the piston ring is rigidly stuck in the piston groove on account of heavy carbon deposits or from other causes, 85 plates 12 of sufficient thickness to fill the seats between the flanges 11 and the ring 1 may be inserted therein, said plates having the fingers 14 and lips or hooks 15 but without the stop lugs or abutments 13, as in such cases 90 the latter are not necessary.

From the foregoing it will be seen that a simple, strong and durable device has been provided which may be employed for expanding piston rings and for removing rings that 95 have become stuck in the grooves of pistons, and that the device is applicable to different sizes and kinds of rings having different forms of joints, the device being adapted to be manufactured and sold at a low cost in the 100 form of a set having several compression rings 1 and a plurality of detachable plates 12 provided with appropriate abutments 13 and fingers 14 to properly cooperate with the various kinds of piston rings in use.

What is claimed is:—

1. A piston ring tool of the character described comprising a resilient split ring adapted to surround a piston, opposed outstanding lugs mounted at the ends of the 110 split ring, said lugs having circumferential extensions provided with means for detachable connection with the split ring, said lugs and extension also having seats in their inner faces, detachable plates adapted to be held in the seats and having means for engaging the ends of a piston ring within the groove of a piston, and means for forcing the lugs apart to expand the piston ring and free same from said groove.

2. A piston ring tool of the character described comprising a resilient split ring adapted to surround a piston, opposed outstanding lugs mounted at the ends of the split ring, said lugs having circumferential extensions provided with means for detachable connection with the split ring, said lugs and extension being wider than the ring and extending to one side thereof to form laterally offset portions, said offset portions hav-

ing arcuate seats formed in their inner faces, arcuate plates adapted to be detachably held in said seats and having inwardly directed fingers terminating in lips for engaging 5 under the overlapped ends of a piston ring within the groove of a piston, and a thumb bolt for forcing the lugs apart to expand the piston ring.

3. A piston ring tool of the character de-
10 scribed comprising a spring metal split ring adapted to surround a piston or a piston ring, outstanding lugs mounted at the ends of the split ring, means for detachably connecting the lugs to the ring, one of said lugs having a
15 threaded aperture, the other lug being provided with a longitudinally elongated opening in alinement with the threaded aperture, the last-named lug also having a transverse slot extending inwardly from its outer end
20 and beyond the inner end of said elongated opening, a metal plate adapted to be inserted into said transverse slot to close the said elongated opening, a reversible thumb bolt having threads at one end to engage the
25 threaded aperture in one lug and to bear at its end against said metal plate in the other lug to cause a separation of the lugs, and means carried by the latter to engage the ends of a piston ring and expand the same as
30 the lugs are separated.

4. A device of the class described comprising a resilient, split ring having radially disposed apertures spaced from the ends thereof, outwardly extending pins or studs mounted
35 on the ring adjacent to the ends thereof, outwardly projecting lugs having circumferential base portions extending oppositely to each other and provided near their outer ends with apertures adapted to register with
40 the apertures in the ring, said base portions also having sockets formed therein to receive the pins or studs, headed screws passing outwardly through the alined apertures, wing nuts threaded thereon to bind the lugs to the ring, and means for forcing the lugs away
45 from each other.

5. A device of the class described comprising a resilient split ring, outstanding, normally parallel lugs detachably connected to the ends of the ring, said lugs having base portions provided with seats on their inner curved faces, a threaded thumb bolt traversing one of the lugs, a plate attachable to the

other lug to abut the end of the bolt to force the lugs apart, and means located in said 55 seats to engage the ends of a piston ring while seated in the groove of a piston and to expand and pull the same out of said groove, said means being removable and interchangeable with similar means of different sizes to 60 accommodate different kinds and sizes of piston rings.

6. A device of the class described comprising a resilient split ring, outstanding, normally parallel lugs detachably connected 65 to the ends of the ring, said lugs having base portions provided with seats on their inner curved faces, a threaded thumb bolt traversing one of the lugs, a plate attachable to the other lug to abut the end of the bolt to force the lugs apart, said base portions each having a radial opening at the centers of the seats, arcuate plates adapted to be placed within the seats at one side of the split ring and having a central threaded stud traversing said 70 opening and provided with a wing nut to detachably connect the plates in the seats, inwardly directed fingers extending from the plates at their inner ends and having lips adapted to be engaged beneath the interfitting ends of a split piston ring to expand the same, said arcuate plates also having inwardly directed guide lugs at their outer ends 75 to engage the sides of the piston ring, said arcuate plates being removable and interchangeable with similar plates having fingers and guide lugs of different widths to accommodate different kinds and sizes of piston rings.

7. A device of the class described comprising a resilient ring split at one point and having a detachable lug at each abutting end, said lugs having offset base portions projecting at one side of the split ring, piston ring engaging means adapted to be seated in the 90 inner faces of the offset base portions to engage and expand the piston ring when the latter is located to one side of the split ring and means to force the lugs apart, said piston ring engaging means being removable and 95 interchangeable with similar means of different sizes to accommodate different kinds and sizes of piston rings.

In testimony, that I claim the foregoing as my own, I have hereto affixed my signature.

JOSEPH MATECHIK.
